Primary Examiner — Catherine A Tuttle(74) *Attorney, Agent, or Firm* — Klarquist Sparkman, LLP(57) **CLAIM**

We claim the ornamental design for a golf ball, as shown and described.

DESCRIPTION

FIG. 1 is a front elevation view of a golf ball showing the new design.

FIG. 2 is a rear elevation view thereof.

FIG. 3 is a right side elevation view thereof.

FIG. 4 is a left side elevation view thereof.

FIG. 5 is a top plan view thereof.

FIG. 6 is a bottom plan view thereof; and,

FIG. 7 is an enlargement of the area indicated by circle 7 in FIG. 1.

The broken lines depict features of the golf ball that form no part of the claimed design. The broken lines denoting the circumscribed area in FIG. 1 likewise form no part of the claimed design.
